VIDEO SIGNAL CONTROL SYSTEM

Louis F. Mayle, Fort Wayne, Ind., assignor to
 Farnsworth Television and Radio Corporation,
 a corporation of Delaware

Application September 19, 1942, Serial No. 458,928

7 Claims. (Cl. 178—7.2)

This invention pertains generally to television systems and more particularly to a method and apparatus for controlling and adjusting the gamma of television signals.

It is known in the art that the quality of a reproduced television image may be impaired as a result of the fact that detail effects such as are given to a picture by its natural color, are lost. Also television transmitting apparatus may be of such a nature that video signals are distorted and decreased in level to such an extent that the reproduced signal does not create a faithful image of the initial picture subject matter. Furthermore, each element of a reproduced television image may be exactly proportional in brightness to the corresponding element of the original image and, therefore, the reproduced image may appear flat and lack efficient contrast to be interesting to an observer. This effect may be the result of the fact that the contrast ratio and average brightness of the reproduced image is generally lower in comparison to the corresponding characteristics of the picture being transmitted. Therefore, it is frequently desirable in television transmission that video frequency signals be distorted in certain portions of their amplitude range for providing better fidelity of reproduction. Such distortion is known as gamma control, more particularly defined as the slope of the input-output or stimulus response curve of the system plotted to a logarithmic scale. There are known in the prior art, various devices for controlling the gamma of video frequency signals to provide faithful reproduction of television images whereby the contrast between the light and dark portions of a television image is increased. These devices are subject to several disadvantages in that adjustments therein affect the overall gain of the system and the brightness level of the reproduced scene. Furthermore, prior art devices for controlling the gamma of video frequency signals generally can provide a gamma greater than unity but not a gamma less than unity.

Accordingly, it is an object of the present invention to provide a novel method and apparatus for adjusting the gamma of video frequency signals in a television system.

Another object of this invention is to provide, in a television system, apparatus for imparting a gamma to a video frequency signal which may be either greater or less than unity.

It is a further object of this invention to provide, in a television system, a video signal translating device for varying the gamma of a video

frequency signal without affecting the overall magnitude of that signal.

A still further object of this invention is to provide, in a television system, a signal translating channel for controlling the gamma of a video frequency signal and imparting overall gain to that signal.

There is provided, in accordance with this invention, a signal translating channel in a television system which consists of a multi-electrode electronic device for controlling the gamma of a video frequency signal. The electronic device should preferably comprise at least two control electrodes and an anode, one control electrode having an input voltage-anode current characteristic which tends to provide a gamma greater than unity, the other control electrode having an input voltage-anode current characteristic which tends to provide a gamma less than unity. The gamma control channel is connected in the video frequency amplifier circuit by means of a voltage-dividing device such as a pair of oppositely connected potentiometers, one potentiometer being connected through its adjustable tap to one control electrode of the electronic device and the other potentiometer being connected through its adjustable tap to the other control electrode of the electronic device, thereby to provide a means for dividing a video signal and applying a portion thereof to each control electrode of the electronic device. The adjustable taps on the oppositely connected potentiometers are preferably mechanically connected to provide a common control which may be adjusted to increase the voltage drop across one potentiometer and simultaneously decrease the potential across the other potentiometer. Thus, the portion of video frequency signal impressed on each control electrode may be varied to exactly apportion the video frequency signal between the two control electrodes. Since the characteristic of one control electrode has a gamma or exponent greater than unity and the characteristic of the other electrode has a gamma or exponent less than unity, each portion of the video frequency signal may have imparted thereto a gamma either greater or less than unity.

For a better understanding of the invention together with further objects and advantages thereof, reference is made to the following description taken in connection with the accompanying drawings, and its scope will be pointed out in the appended claims.

In the drawings:

Fig. 1 is a circuit diagram of a complete tele-

vision transmitting system illustrating conventional portions of the system in schematic form and including a video frequency signal translating channel embodying the present invention.

Fig. 2 is a graph, illustrating the grid voltage plate current characteristics of the control electrodes of the signal translating channel.

Fig. 3 is a graph, illustrating the operation, under certain conditions, of the signal translating channel shown in Fig. 1.

Fig. 4 is a graph, illustrating the operation, under certain conditions, of the signal translating channel, shown in Fig. 1.

Referring to Fig. 1 of the drawings, the television transmitting system includes a conventional picture pickup tube 1, an object 2 and a lens system 3 for focussing an image on the screen 5 of tube 1. The tube 1 is provided with electron gun 7 and a power supply 12 to provide an electron beam for scanning screen 5. This tube is illustrated by way of example, as conventional in the television art, and it is not intended that this invention shall be limited to use with any particular type of pickup device.

The cathode ray beam of tube 1 is deflected by means of plates 9 and 10 which are connected to a source of line scanning waves and field scanning waves 13 and 14 respectively. The sources 13 and 14 are controlled by the synchronizing pulse generator 16 in a manner well known in the prior art. The output of screen 5 in tube 1 is impressed across the output resistor 18 connected to the input circuit of the picture signal amplifier 20, there being a connection 21 provided between synchronizing and blanking pulse generator 16 and picture signal amplifier 20 for impressing a blanking pulse on amplifier 20 as is well known in the prior art.

There is provided in accordance with this invention, a signal translating channel 25 connected to the output circuit 22 of picture signal amplifier 20 and the output circuit 26 of channel 25 is connected to a conventional radiant energy transmitter 30 wherein the video frequency signal is impressed on a carrier and radiated by antenna 31.

Signal translating channel 25 consists of the multi-electrode electronic device 32 and a voltage dividing device consisting of potentiometers 34 and 35 mechanically connected in tandem. Such a connection is well known to those skilled in the art and is, therefore, not shown in detail. Electronic device 32 is chosen to have the grid voltage-anode current characteristics shown in Fig. 2. Curve A, the grid voltage-anode current characteristic of grid 40, has an exponent or gamma less than unity. Curve B, the grid voltage-anode current characteristic of grid 41, has an exponent or gamma greater than unity. For ideal gamma control in accordance with this invention, curves A and B of Fig. 2 should be complementary, but satisfactory gamma control is obtainable even though these curves are not exactly complementary. Curves A and B are substantially parabolic in form and, therefore, follow the equation $X = y^a$ where exponent a is the gamma.

The grid voltage-anode current characteristics of grids 40 and 41 may be illustrated also on a log-log scale by converting the equation $y = X^a$ to its logarithmic form which is $\log y = a \log X$ and plotting a logarithmic graph. Curves A and B would then be straight lines the slopes of which would be determined by the gamma or term a in the logarithmic equation. If gamma is chosen

to equal unity, the resulting curve would describe an angle of 45° with respect to the abscissa. If the gamma is chosen as greater than unity, the resulting curve would describe an angle greater than 45° with respect to the abscissa. If gamma is chosen as less than unity the reverse is true.

Potentiometer 34 is connected across the output circuit 22 of picture signal amplifier 20 and 10 potentiometer 35 is connected in parallel with potentiometer 34 by the cross connection 36. The sliding contacts 37 and 38, of potentiometers 34 and 35 respectively, are connected to the control electrodes 40 and 41 respectively, of tube 32. Sliding contacts 37 and 38 are mechanically connected, as indicated at 39, to provide a common control for potentiometers 34 and 35, such that each sliding contact may be simultaneously moved in the same direction. Control electrodes 40 and 41 are biased through grid resistors 44 and 45 respectively in accordance with the potential drops as determined by the adjustments of the taps of bias resistor 46 which is connected to a source of biasing potential, C-. The anode 42 of tube 32 is connected to transmitter 30 and to a source of anode potential B+ together with a peaking circuit consisting of resistor 46 and inductance 47 which is conventional in the prior art. The remainder of the signal translating channel consists of well known circuit elements and connections and, therefore, it is not necessary that they be explained in detail. It should be noted that signal translating channel 25 may be an integral part of amplifier 20 but for purposes of illustration it is shown as a separate unit.

The circuit illustrated in Fig. 1 with the exception of channel 25, operates in a conventional manner and, therefore, will only be described in a brief manner. The screen 5 of tube 1 is scanned under the control of deflecting plates 9 and 10 by a cathode ray beam to impress a video frequency signal consisting of a chain of electrical impulses across the resistor 18 representative of the successively scanned elemental areas of the object 2. The video frequency signal appearing across resistor 18 is amplified in a conventional manner by picture signal amplifier 20 and impressed on the output circuit 22.

Signal translating channel 25 imparts a gamma to the picture signal either greater or less than unity depending upon the adjustment of the potentiometers 34 and 35, and upon the gamma of the video signal delivered by the picture pickup device. Since the adjustable sliding contacts 37 and 38 are mechanically connected as indicated at 39, they may be adjusted simultaneously to move upwardly or downwardly, increasing the output of one from zero to maximum and decreasing the output of the other from maximum to zero. Thus, for purposes of illustration, it may be assumed that the mechanical connection 39 simultaneously moves sliding contacts 37 and 38 upwardly or downwardly so that the signal appearing in the output circuit 22 may be divided in any desired proportions between the control electrodes 40 and 41.

Fig. 3 illustrates, by means of a graph, the results when the voltage across the output circuit 22 is impressed on the grid 40 or grid 41 of tube 32. It also illustrates the results when one-half of the voltage across output circuit 22 is impressed on each of the grids 40 and 41. Curve e in Fig. 3 represents the full video voltage across output circuit 22. For purposes of example, curve

e represents a video voltage wave moving eight equal increments of brilliance from black to white, and whose gamma is unity. Let it be assumed that the sliders 37 and 38 are first adjusted to their lowermost positions so that full voltage e is impressed on grid 41 and zero video voltage on grid 40. When voltage curve e is projected point by point on curve B, the characteristic of grid 41, the voltage resulting in the output of tube 23 is represented by curve C. Curve B is assumed to have an exponent or gamma greater than unity. For purposes of example, curve B has an exponent of 2. Thus, the video output at 22 has had its gamma increased by a factor of 2. Since curve e had a gamma of 1, curve C has a gamma of 2. From inspection of curve C it is apparent that the black portion of the signal is expanded while the white portion is contracted. Thus black portions of the transmitted picture are emphasized with respect to its white portions.

If the potentiometer setting is changed so that both sliders 37 and 38 are moved upwardly to the upper limit of their movement, full video voltage e is impressed on the grid 40 and there is zero video voltage on grid 41. Again referring to Fig. 3, there is shown a projection of curve e to curve A, which is the characteristic of grid 40, and voltage H' appears in the output of tube 32, this voltage having a gamma corresponding to that of curve A which is for this example, equal to $\frac{1}{2}$. Inspection of curve H' reveals that the white portion of the signal is expanded and the black portion is contracted thereby to emphasize the white portions of the transmitted picture with respect to its black portions. In this case the gamma of curve e has been changed from 1 to $\frac{1}{2}$ as represented by curve H' .

By adjusting the sliders 37 and 38 of the potentiometer to the half-way position, one-half of the voltage e is impressed on each of the grids 40 and 41. There is illustrated in Fig. 3 by the curve $\frac{1}{2}e$. Projecting this curve to the curves A and B there results the curves D' and D respectively. The curve D' having a gamma of one-half and curve D having a gamma of 2. By adding these two curves, there is obtained the output voltage which appears in the anode circuit of tube 32. This is illustrated by the curve $D+D'$ which has a gamma of approximately one since it lies in substantially a straight line. In this case there is substantially no distortion of signal. Thus, the transmitted picture is not distorted as regards contrast between black and white.

Fig. 4 of the drawings illustrates the results when the potentiometer is adjusted to impress $\frac{3}{4}$ of the output voltage in circuit 22 on one grid and $\frac{1}{4}$ of the output voltage on the other grid. In the first instance, let it be assumed that the potentiometer is adjusted downwardly to the point where $\frac{3}{4}$ of the output voltage in circuit 22 is impressed on grid 41 and $\frac{1}{4}$ of the output voltage in circuit 22 is impressed on grid 40. Projecting the curve $\frac{3}{4}e$ to the curve B, there is obtained voltage component F having a gamma of 2. Projecting the curve $\frac{1}{4}e$ to the curve A, there is obtained a voltage component F' having a gamma of $\frac{1}{2}$. Adding curves F and F' there is obtained a curve $F+F'$ having a gamma greater than unity and expanding in amplitude the black portion of the signal, and contracting the white portion, but not as much as represented by curve C of Fig. 3.

Reversing the above procedure, the potentiometer is adjusted upwardly until the sliders 37 and 38 impress $\frac{1}{4}e$, e being the output voltage in circuit 22, on grid 41 and $\frac{3}{4}e$ on grid 40. By

projecting the curve $\frac{3}{4}e$ on the curve A, there is obtained a voltage component G', and by projecting the voltage $\frac{1}{4}e$ on curve B, there is obtained a voltage component G. By adding curves 5 G and G' there is obtained a curve $G+G'$ having a gamma less than unity and illustrating that the white portion of the signal is expanded in amplitude, while the black portion is contracted, but not as much as represented by curve H' of 10 Fig. 3.

From the above, it is evident that this invention provides a signal translating channel in which there may be imparted to a video frequency signal, a gamma either greater or less than unity. 15 Furthermore, this result is obtained without affecting the overall magnitude of the video frequency signal.

The curves A and B of Figs. 3 and 4 are plotted to have an arbitrary exponent or gamma for purposes of illustration, but it will be obvious to those skilled in the art that the shape or exponent of such curves is dependent upon the grid characteristics of the particular tube utilized in the signal translating channel. It has been found that a 20 tube conventionally designated as a 6L7 has characteristics such as those illustrated in Fig. 2. One characteristic having a gamma greater than unity and the other characteristic having a gamma less than unity. Any multi-electrode vacuum 25 tube whose grid characteristics are similar to those illustrated in Fig. 2 may be utilized in a signal translating channel for the purposes of accomplishing the objects of this invention and, therefore, it is not intended that this invention 30 shall be limited to the particular vacuum tube 35 illustrated herein.

It should be understood that different degrees of gamma control may be introduced in a television system to compensate distortion of a video 40 frequency signal which may result, for example, from the particular type of picture pickup tube which is used, or from the particular transmitting or receiving channel. The curves A and B, such as illustrated in Fig. 2 of the drawings, need 45 not have a gamma greater than unity and also less than unity by reason of the fact that distortions of the signal may require that one curve have a gamma of unity and the other have a gamma greater than unity. It may be desirable that both curves have a gamma greater than unity or less than unity or it may be desirable that a portion of each curve have a gamma of unity and another portion have a gamma greater or less than unity. From this it will be obvious 50 to those skilled in the art that it is within the scope of this invention to provide a gamma adjusting channel for distorting a video frequency 55 signal to any degree which may be necessary to correct distortion introduced by one or more elements of the television system.

In the drawings there is illustrated a signal translating channel 25 the circuit elements of which have been assigned specific electrical values but these have been disclosed for purposes of illustration only, and it is not intended that the invention shall be limited to a circuit of those 60 specific values.

While there has been described what is at present considered the preferred embodiment of the invention, it will be obvious to those skilled in the art, that various changes and modifications may be made therein without departing from the invention, and it is, therefore, aimed in the appended claims to cover all such changes and modi-

fications as fall within the true spirit and scope of the invention.

What I claim is:

1. A television signal translating system comprising a signal channel, a first means for controlling a flow of electrons, a second means for controlling a flow of electrons, the input voltage-anode current characteristic of said first means providing a gamma greater than unity, the input voltage-anode current characteristic of said second means providing a gamma less than unity, and a voltage dividing means coupled between said channel and said first and second means for dividing the television signal and impressing it on each of said first and second means to impart a gamma to the resulting signal which may be either greater or less than unity.

2. A television signal translating system comprising a signal channel, a multi-electrode electronic device, the input voltage-anode current characteristic of one electrode providing a gamma greater than unity, the input voltage-anode current characteristic of another electrode providing a gamma less than unity, and a voltage dividing means coupled between said channel and said electrodes for simultaneously dividing the television signal and impressing it on each of said electrodes to impart a gamma to the resulting signal which may be either greater or less than unity.

3. A television signal translating system comprising a signal channel, a multi-electrode electronic device, the input voltage-anode current characteristic of one electrode providing a gamma greater than unity, the input voltage-anode current characteristic of another electrode providing a gamma less than unity, a first output potentiometer coupled between said channel and said one electrode, a second input potentiometer coupled between said channel and said other electrode and control means for operating said potentiometers to increase the output of one potentiometer and decrease the output of the other potentiometer whereby the television signal may be divided and impressed on each of said electrodes to impart a gamma to the resulting signal which may be either greater or less than unity.

4. A television signal translating system comprising a television channel, a multi-grid elec-

tronic device, the input voltage-anode current characteristic of one grid providing a gamma greater than unity, the input voltage-anode current characteristic of another grid providing a gamma less than unity, a first input potentiometer coupled between said channel and said one grid, a second input potentiometer coupled between said channel and said other grid and control means common to said potentiometers for operating them to increase the output of one potentiometer and simultaneously to decrease the output of the other potentiometer whereby the television signal in said channel may be divided and impressed on each of said grids to impart a gamma to the resulting signal which may be either greater or less than unity.

5. The method of translating a television signal comprising the steps of dividing a video signal into at least two components, imparting a gamma greater than unity to one of said components, imparting a gamma less than unity to the other of said components and combining said components to obtain a signal having a gamma either greater or less than unity.

6. The method of translating a television signal comprising the steps of dividing a video signal of a given voltage into voltage components the sum of which is equal to said given voltage, imparting a gamma greater than unity to one of said components, imparting a gamma less than unity to the other of said components and combining said components to obtain a signal having a gamma either greater or less than unity and an amplitude substantially equivalent to the amplitude of said video signal.

7. The method of translating a television signal comprising the steps of dividing a video signal of a given voltage into voltage components the sum of which is equal to said given voltage, impressing each component on a different grid of an electron tube, imparting a gamma greater than unity to one of said components, imparting a gamma less than unity to the other of said components and controlling the output of said electron tube by said components to obtain a signal having a gamma either greater or less than unity and a magnitude substantially equivalent to the magnitude of the input signal.

LOUIS F. MAYLE.
